A. D. GROVER,
MAGNETIC SLUG DEFLECTOR FOR COIN CONTROLLED MACHINES,
APPLICATION FILED JULY 3, 1916.

1,261,121.

Patented Apr. 2, 1918

INVENTOR.

Albert D. Grover.

UNITED STATES PATENT OFFICE.

ALBERT D. GROVER, OF NEW YORK, N. Y., ASSIGNOR TO AUTOSALES GUM AND CHOCOLATE COMPANY, A CORPORATION OF NEW YORK.

MAGNETIC-SLUG DEFLECTOR FOR COIN-CONTROLLED MACHINES.

1,261,121.

Specification of Letters Patent.

Patented Apr. 2, 1918.

Original application filed December 17, 1914, Serial No. 877,647. Divided and this application filed July 3, 1916. Serial No. 107,229.

To all whom it may concern:

Be it known that I, ALBERT D. GROVER, a citizen of the United States, and a resident of New York city, in the county of New York and the State of New York, have invented certain new and useful Improvements in Magnetic-Slug Deflectors for Coin-Controlled Machines, of which the following is a specification.

10 The object of my invention is to provide a simple and effective means for deflecting iron slugs out of the coin-chute of a coin-controlled machine, so as to prevent such spurious tokens from reaching an operative position within the machine.

15 This application is a division of my co-pending application, Serial No. 877,647, filed December 17, 1914, and I have, therefore, not deemed it necessary to illustrate more than a section of the coin-chute with the associated magnetic deflector.

20 The drawing accompanying this specification comprises a single figure which shows a longitudinal section of a coin-chute provided 25 with my invention.

The upper opening 1 of the coin-chute is arranged in alinement with the coin-entrance slot of the machine, while the lower or exit end 2 is adapted to guide the coin into proper 30 position within the machine. As it is not necessary to an understanding of my invention what the coin does after leaving the coin-chute, no coin-controlled mechanism need be shown or described. A permanent 35 U-shaped magnet M is so fixed in position, by any suitable means, with respect to the coin-chute that the upper edge 3 thereof is substantially parallel with the wall 4 of the coin-chute. The magnet, or at least that 40 portion of it which extends into the coin-chute, is arranged in the plane of the coin-chute itself. The upper edge 3 of the magnet and the wall 4 form the first section of the zigzag coin-chute. The vertical wall or 45 edge 5 of the coin-chute comes opposite the point 6 of the pole p of the magnet, while the wall 7 is substantially parallel to the polar faces 8. The angular arrangement of the walls 5 and 7 is such that the deposited coin 50 or check will roll closely about the point 6 and then pass in very close proximity (as closely as mechanical conditions will permit) to the polar faces 8.

When a good coin is deposited, it passes

from between the polar faces 8 and the wall 55 7 into the passageway 9 formed by the parallel walls 10 and 11, and thence downwardly into operative position.

However, when the deposited check or disk is of magnetic material, it will be held attracted to the magnet and when it moves past the polar faces it will not drop into the passageway 9, as in the case of a non-magnetic disk, but will be held by the magnet and caused to swing about the edge 12 of the pole p', which forms the last point of contact between the magnet and the magnetic disk. In proper position with respect to the edge 12 of the magnet is fixed a non-magnetic pin or stud 13 which extends into the plane of the magnet, or at least of the poles thereof. Now, as the descending magnetic disk swings about the point 12, it strikes the pin 13 and thereby breaks contact with the magnet, with the result that the disk falls out of the coin-chute through the discharge opening 14 formed between the magnet, and the upper edge 15 of the wall 11. In the drawing, the dotted circle C indicates either a good coin or a magnetic disk as it begins to roll past the polar edges 8. The dotted circle C' indicates the position of a magnetic disk which has been stripped from the polar edge 12 by coming into contact with the fixed pin 13 and is ready to drop out of the coin-chute 80 through the opening 14.

85 It will be seen from the above that I have provided a very simple and effective deflector for magnetic slugs. My invention is particularly effective for diverting thin, light 90 magnetic disks which are usually very difficult to get rid of in coin-controlled machines and frequently cause considerable trouble, as actual experience has shown.

95 Another advantage of my invention, as will be clear from the above, resides in the fact that magnetic slugs are positively prevented from being snapped past the magnet. This is due to the arrangement of the magnet, or at least the poles thereof, to form part of the inclined wall of the coin-chute. If the inserted coin should be snapped into the coin-opening 1, it will first strike the edge 3 of the magnet and then roll into the angular space formed by the walls 5 and 7, so that when the inserted disk begins to roll over the inclined wall 7 past the polar faces, it will have lost all of its initial velocity and 100 105

will simply roll down by gravity with sufficient slowness to allow the magnet to exert its full influence on the disk. Even if a person should succeed in speeding the inserted 5 magnetic slug over the edge 3 of the magnet, its increased momentum (that is to say, the momentum due to an initial velocity) will be effectively arrested by the walls 5 and 7.

While I have herein shown a specific configuration and arrangement of coin-chute and magnet, I would have it understood that I do not intend to be limited to such details, as the shape, proportion and arrangement of the parts may be modified and still embody 15 the invention as described in the appended claims:

1. In a coin-controlled machine, a coin-chute lying in a substantially vertical plane and having a downwardly inclined section, a 20 U-shaped magnet mounted at an angle so that its limbs extend downwardly toward the bottom wall of said inclined section, the polar faces of said magnet being opposite to and substantially parallel with said bottom wall to form the top of said inclined section, whereby a magnetic check rolls over 25 said inclined bottom wall in magnetic contact with both polar faces, and a non-magnetic stop arranged near the lower pole-tip 30 of the magnet to strip the magnetic disks

from said pole-tip and swing them out of the coin-chute.

2. In a coin-controlled machine, a coin-chute having a downwardly inclined coin-entrance section and a downwardly inclined 35 coin-testing section arranged at an angle to said first section, so that the momentum of a deposited check is arrested in passing from the first section to the second, a downwardly extending U-shaped magnet so mounted that 40 its upper limb forms the lower wall of said coin-entrance section and the polar faces form the top of said inclined coin-testing section, whereby a deposited check rolls over said upper limb and is then forced to travel 45 through said section under both polar faces in close proximity thereto, so that a magnetic check rolls past said polar faces in magnetic contact therewith, and a non-magnetic stop arranged near the lower pole-tip 50 of the magnet to strip the magnetic disks from said pole-tip and swing them out of the coin chute.

In witness whereof, I hereunto subscribe my name this 29 day of June, 1916.

ALBERT D. GROVER.
